GAME APPARATUS

Jay C. Moore, Fredonia, Pa.

Application January 2, 1940, Serial No. 312,119

2 Claims. (Cl. 265—20)

This invention relates to game apparatus provided with indicating means, operated by an impact delivered from a blow of a striking implement.

5 An object of the invention is to provide a weighted indicator guide adjacent a scale means for determining a score.

Another object of the invention is to provide a vibrating and binding non-synchronized motion of the indicating means on its guide.

A further object of the invention is to provide a cushioning means moulded into a weighted indicator and having a reinforced base to absorb shock from impinging action thereon.

15 A further object is to provide apparatus of this character which will be formed of a few strong simple and durable parts, which will be inexpensive to manufacture, and which will not easily get out of order.

20 With the above and other objects in view the invention consists of certain novel details of construction and combinations of parts hereinafter fully described and claimed, it being understood that various modifications may be resorted to 25 within the scope of the appended claims without departing from the spirit or sacrificing any of the advantages of the invention.

In the accompanying drawing forming a part of this specification:

30 Figure 1 is a perspective view of the invention showing the indicator in dotted lines in indicating position.

Figure 2 is a longitudinal sectional view of the invention with parts in elevation.

35 Figure 3 is a fragmentary plan of the invention with the guiding means for the indicator shown in section.

Figure 4 is a bottom plan of the indicating washer.

40 Figure 5 is a detail sectional view of the indicating washer mounted on a section of the guiding means.

45 Referring now to the drawing in which like characters of reference designate similar parts in the various views, 10 designates a riser or guide rod which is disposed vertically and is anchored at the bottom to one end of a substantially rectangular base 11, although the base may be of any other desired shape. The rod extends through an opening in the base and is provided on the bottom with a flange 12 which engages the underneath face of the base. A ring 13 is slidably mounted on the rod and engages the top face of the base. Bolts 14 are passed through the ring,

the base and the flange to rigidly secure the rod to the base.

A pair of vertical brackets 15 are secured near the center of the base on opposite sides of the longitudinal medium line of the base by bolts 16 5 or other connectors. The brackets receive the gudgeons 17 of a substantially flat bar-like rock shaft 18.

A strike lever 19 in the nature of an elongated plate or board is secured near the center to the 10 rock shaft by bolts 20 or other connectors. One end of the strike lever is bifurcated as shown at 21 to loosely receive the rod 10. A rubber plate 22 is secured to the top face of the pivoted end of the strike lever, and is adapted to receive blows 15 of a mallet or similar device. A resilient pad 23 is secured to the base underneath the pivoted end of the strike lever to absorb the shock of the mallet blows.

A helical spring 24 is loosely sleeved on the 20 guide rod 10 and is formed integral at the upper end with a washer-like weight 25 which is slidably and loosely sleeved on the rod 10. The lowermost convolutions of the spring are enlarged to form a reinforcing annular base 26 for the 25 spring. The reinforcing annular base is supported upon the bifurcated end 21 of the strike lever.

The riser rod 10 is provided at the upper end with a scale 27 to indicate the height to which 30 the weight 25 rises under impulse of the bifurcated end of the strike lever when the player strikes the pivoted end of the lever with the mallet. The riser rod is resilient and in practice it vibrates while the weight is in movement and 35 this vibration has been found to keep the weight from rising too high on the rod.

The base is provided at the corners with short supports 28 to elevate the same above the ground, 40 a game table, or other support upon which the base may be placed.

In operation when the player strikes the pivoted end of the strike lever with the mallet the bifurcated end of the strike lever impinges 45 against the reinforcing base 26 of the spring and compresses the spring to shoot the weight 25 upwardly on the riser rod 10 to a height commensurate with the force of the blow on the lever. During upward movement of the weight the rod 50 vibrates and the spring 24 also vibrates so that the walls of the opening in the weight have intermittent frictional engagement with the rod, as also does the convolutions of the spring, and thus a breaking action or binding action occurs 55

which retards upward movement of the weight on the riser rod.

From the above description it is thought that the construction and operation of the invention will be fully understood without further explanation.

What is claimed is:

1. A game apparatus comprising a base, a guide rod secured to and disposed vertically of the base, a striking lever pivoted on the base and being provided with a bifurcated end receiving the rod near its base, a coil spring encasing the rod and having a reinforced base resting on the bifurcated

end, a weighted washer integral with the upper end of the coil spring, and a strike plate adapted to receive impact on the free end of the lever, rocking the lever on its pivot forcing the washer and spring upwardly on the rod.

2. A game apparatus comprising a rod, a base supporting the rod vertically thereon, a spring having closely associated lower convolutions slidably supported on the rod, a weight on the top of the spring slidably received on the rod, and a strike lever pivoted between its ends on the base and contacting said convolutions.
